(57) **ABSTRACT**

A self-priming dedicated water feature pump is provided. The water feature pump can include a strainer housing connected to a pump housing. The strainer housing can include a reservoir for allowing water to enter the strainer housing so that the pump can self-prime. The strainer housing can also include a post installed within the reservoir. The post can function to prevent a strainer basket from being installed in the strainer housing. The post can be of sufficient volume and/or geometry to allow enough water to enter the strainer housing so that the water feature pump can self-prime while also preventing a strainer basket from being installed in the strainer housing.

FIG. 10

SELF-PRIMING DEDICATED WATER FEATURE PUMP

RELATED APPLICATIONS

This application claims priority to U.S. Provisional Patent Application No. 62/398,228 filed on Sep. 22, 2016, the entire disclosure of which is incorporated herein by reference.

BACKGROUND

Field

The present invention relates to a pump, and, more specifically to a self-priming pump that is dedicated to pumping water to water features.

Related Art

A swimming pool has a filtration pump. The filtration pump of a swimming pool pumps water to the swimming pool and is therefore a key component of the circulation system in a pool. Filtration pumps are typically installed upstream of the pool filter. Because of this, filtration pumps include a strainer basket for removing large debris from the water and preventing the debris from entering the pump.

A swimming pool could also have added water features such as a spa, fountain, waterfall, etc. These water features may have a dedicated pump to provide circulation to that water feature. Pumps that provide circulation to water features are typically installed after the pool filter and therefore do not need a strainer basket. However, in the pool market today, filtration pumps are often used to supply water to the water features which renders the strainer basket of the filtration pump superfluous. Furthermore, there are dedicated water feature pumps without the strainer basket and without the reservoir where the strainer basket is installed. However, without the reservoir, dedicated water feature pumps of swimming pools are not known to self-prime.

Accordingly, there is a need for improvements in the design of water feature pumps where the water feature pumps can self-prime and also prevent a strainer basket from being installed in the water feature pump.

SUMMARY

A self-priming dedicated water feature pump is provided. The water feature pump can include a strainer housing connected to a pump housing. The strainer housing is an example embodiment of a priming reservoir, and references herein to the example embodiment of the strainer housing, shall be understood by a person of ordinary skill in the art to also encompass a reference to a priming reservoir more generally. The strainer housing can include a reservoir for allowing water to enter the strainer housing so that the water feature pump can self-prime. The strainer housing can also include a post installed within the reservoir. The post can function to prevent a strainer basket from being installed in the strainer housing. The post can be of sufficient volume and/or geometry to allow enough water to enter the strainer housing so that the water feature pump can self-prime while also preventing a strainer basket from being installed in the strainer housing. A cap can also be installed on the post to prevent a strainer basket from being installed in the strainer housing. The cap can be removable to allow for debris removal.

BRIEF DESCRIPTION OF THE DRAWINGS

The foregoing features and others will be apparent from the following Detailed Description, taken in connection with the accompanying drawings, in which:

FIG. 1 is a perspective view of an embodiment of a water feature pump of the present disclosure;

FIG. 2 is a sectional view of the embodiment of FIG. 1 taken along line 2-2 thereof;

FIG. 3 is a perspective view of an embodiment of a water feature pump with a cap of the present disclosure;

FIG. 4 is a sectional view of the water feature pump and cap of FIG. 3 taken along line 4-4 thereof;

FIG. 5 is a perspective view of an embodiment of a reservoir cover for a strainer housing of a water feature pump;

FIG. 6 is a perspective view of an embodiment of a water feature pump with a plurality of ribs;

FIG. 7 is a top view of an embodiment of a water feature pump and a plurality of ribs;

FIG. 8 is a side view of an embodiment of a water feature pump with a remotely installed strainer housing;

FIG. 9 is a schematic side view of an embodiment of a strainer housing with a top cover of the water feature pump; and

FIG. 10 is a perspective view of an embodiment of a water feature pump with a screen.

DETAILED DESCRIPTION OF THE INVENTION

The present invention relates to a self-priming dedicated water feature pump, as discussed in detail below in connection with FIGS. 1-10.

FIG. 1 is a perspective view of a water feature pump 10 of the present disclosure. The water feature pump 10 includes a strainer housing 12, a pump housing 14, a base 16, and a prevention means for preventing the installation of a strainer basket in the strainer housing 12 (e.g., a post 18).

The strainer housing 12 can be integrally formed with the pump housing 14. The strainer housing 12 can also be connected to the pump housing 14 through other mechanical means such as gluing, fastening or snap-fitting. The strainer housing 12 and the pump housing 14 can define a substantially perpendicular relationship relative to each other, with the strainer housing 12 extending upwardly (vertically) with respect to the base 16 and the pump housing 14 extending rearwardly (horizontally) with respect to the strainer housing 12.

FIG. 2 is a sectional view of the water feature pump 10 of the present disclosure along line 2-2 in FIG. 1. As can be seen, the strainer housing 12 includes a front end 20 and a rear end 22, the rear end 22 being opposite to the front end 20. The strainer housing 12 further includes a top end 24 and a bottom end 26, the bottom end 26 being opposite to the top end 24. The front end 20, the rear end 22, the top end 24, and the bottom end 26 together form an outer wall 28 and an inner wall 29 of the strainer housing 12. The front end 20 can include an inlet 30 for receiving an inflow conduit (e.g., a pipe, a hose, and/or a connector therefor). The inlet 30 can be threaded to receive and secure the inflow conduit. The top end 24 can form an opening to a reservoir 32. The reservoir 32 is an empty cavity shaped by the outer wall 28 and the inner wall 29. The shape of the outer wall 28, the inner wall 29 and the reservoir 30 can be any suitable shape known to those of ordinary skill in the art to accomplish the objectives of the present disclosure as described herein. The size of the

reservoir 32 can be a suitable size to retain a sufficient amount of water as will be discussed in greater detail below.

The reservoir 32 can include a removed portion 34. The removed portion 34 can be located on the rear end 22 of the strainer housing 12 which facilitates water to flow from the strainer housing 12 to the pump housing 14. The pump housing 14 can include an outlet 36 so that the flow of water can move from the inlet 30 of the strainer housing 12 through the removed portion 34 into the pump housing 14 and exit the outlet 36. The outlet 36 can be threaded to receive an outflow conduit for directing the flow of water out of the water feature pump 10 to the water features, such as spa jets, waterfall, fountain, deck jet, laminar, bubbler, vanishing edge, etc.

As noted above, the water feature pump 10 also includes the post 18. The post 18 can include a top portion 38, a body 40, and a bottom portion 42. The post 18 can be shaped in a cylindrical fashion or any other suitable shape to accomplish the function of the present disclosure as will be discussed in greater detail below. The bottom portion 42 of the post 18 can be secured to the bottom of the inner wall 29 which abuts the bottom end 26 of the strainer housing 12. The bottom portion 42 of the post 18 can be secured permanently using any suitable mechanism known to those of skill in the art. For example, the post 18 can be integrally formed with the bottom of the inner wall 29 or fastened mechanically with an adhesive, screw, or snap-fit mechanism. The post 18 can alternatively be removable from the reservoir 32 and need not be permanently affixed to the inner wall 29. As will be discussed in greater detail below, removing the post 18, can allow the water feature pump 10 to be converted from a dedicated water feature pump to a traditional filtration pump. The thickness of the body 40 of the post 18 should be a suitable size in relation to the reservoir 32 to allow for a sufficient amount of water to fill into the reservoir 32. The purpose of allowing a sufficient amount of water into the reservoir 32 will be explained in greater detail below.

An alternative embodiment of the post 18 is shown in connection with FIGS. 3 and 4. More specifically the post 18 could include a cap 44 secured to the top portion 38 (shown in FIG. 1) of the post 18. The cap 44 can include a top side 46 and a bottom side 48. As shown in FIG. 4, the distance between the top side 46 and the bottom side 48 (e.g., the thickness) can be of any distance so as to allow for sufficient amount of water to fill into the reservoir 32. The purpose of allowing a sufficient amount of water will be explained in greater detail below. Furthermore, the cap 44 can be secured to the top portion 38 by any means known to those of skill in the art, including, but not limited to, using an adhesive, screws or a snap-fit mechanism. The cap 44 can be a removable from the post 18 to allow for debris removal. If debris removal is not required, the cap 44 can be secured to the post 18 permanently. Furthermore, the cap 44 can be integrally formed with the post 18 so as to form a single unit secured to the bottom of the inner wall 29 of the strainer housing 12.

In another embodiment, the post 18 can be designed to be removable from the inner wall 29 and reservoir 32. For example, the means for installing the post 18 can be done in a removable manner such by using a screw or a snap-fit mechanism. If such a removable mechanism is used, the post 18 can be removed by unscrewing or snapping out the post 18 from the inner wall 29. Removing the post 18 from the reservoir 32 allows the water feature pump 10 to be transformed from a dedicated water feature pump to a traditional filtration pump. The traditional filtration pump which has no

post 18 allows a strainer basket to be installed in the reservoir 32 and therefore can be installed before a filter and can self-prime. If the post 18 was installed in the reservoir 32 by permanently fastening the post 18 to the inner wall 29, then the present disclosure can allow for a strainer basket to be shaped so that the strainer basket can be installed over the post 18 and be within the reservoir 32. For example, the strainer basket could include a long tube that would accept the post 18 and fit within the reservoir 32 as shown in FIGS. 1 and 2. The strainer basket could also just have an opening or a gap in the bottom of the basket to fit over the post 18 so that when the strainer basket is installed, the opening or gap would fit snug with the post 18 to prevent debris bypass.

The water feature pump 10 can function as a dedicated water feature pump that allows for self-priming while also preventing the installation of a strainer basket. A strainer basket may not be needed for the water feature pump 10 because the water feature pump 10 can be installed after the filter to provide circulation to various water features. It may still desirable to include a strainer housing 12 to allow the water feature pump 10 to self-prime. Therefore, the post 18 can be installed within the reservoir 32 of the strainer housing 12 to prevent installation of a strainer basket. The thickness of the body 40 of the post 18 can be a certain amount relative to the size of the reservoir 32 so to allow a sufficient amount of water to enter the reservoir 32 to allow the water feature pump 10 to self-prime. Alternatively, the volume of the post 18 can be such that it allows for a sufficient amount of water to be available in the reservoir 32 to allow the water feature pump 10 to self-prime. The geometry of the post 18 can be any type of geometry known to those of skill in the art to make it difficult to design a new strainer basket that could be retrofitted to the strainer housing 12. Additionally, the cap 44 can be added to the post 18 such that a strainer basket modified to fit in the strainer housing 12 would need to be so small so as to render it useless.

An alternate embodiment for a water feature pump 10 is shown in FIG. 5. In this embodiment, the strainer housing 12 is covered with a prevention means for preventing the installation of a strainer basket in the strainer housing 12 (e.g., a priming reservoir cover 50). The priming reservoir cover 50 can include a top cover 52, an extended wall 54 and an inlet aperture 56. The top cover 52 and the extended wall 54 can be integrally formed with each other or they can be mechanically fastened to each other by any means known in the art. The priming reservoir cover 50 can be integrally formed with the strainer housing 12 or it can be permanently fastened with the strainer housing 12. If desired, the priming reservoir cover 50 can be mechanically fastened with the strainer housing 12 to allow for removal of the priming reservoir cover 50 from the strainer housing 12. When installed, the extended wall 54 has a diameter just greater than the outer wall 28 of the strainer housing 12 and can be placed (e.g., concentrically) over the outer wall 28 of the strainer housing 12 with any suitable seal (or, in some embodiments, the extended wall 54 has a diameter just less than within the outer wall 28 and can be placed (e.g., concentrically) within the outer wall 28 with any suitable seal). The top cover 52 can fully cover the top end 24 of the strainer housing 12 and thereby prevent a strainer basket from being installed in the reservoir 32. The inlet aperture 56 can be aligned with the inlet 30 to allow for water flow into the strainer housing 12. This configuration prevents a strainer basket from being installed in the strainer housing 12 by virtue of the top cover 52. The extended wall 54 further facilitates tampering and removal of the top cover 52.

from the strainer housing 12. The priming reservoir cover 50 can alternatively be a singular piece of material such as plastic. The reservoir cover 50 can be installed permanently with the strainer housing 12 to prevent installation of a strainer basket in the strainer housing 12, however, the reservoir cover 50 can be mechanically fastened to allow for removal of the reservoir cover 50 if debris removal is desired or if the water feature pump 10 is desired to be converted to a traditional filtration pump. In this embodiment a post 18 is not necessary to prevent installation of the strainer basket, and therefore can allow more water in the reservoir 32 to allow the pump 10 to self-prime. The post 18 can be included to provide for an additional means for preventing the installation of the strainer basket in the strainer housing 12.

An alternate embodiment of the water feature pump 10 is shown in FIG. 6. A top-down view of this embodiment is shown in FIG. 7. In this embodiment, the strainer housing 12 includes a prevention means for preventing the installation of a strainer basket in the strainer housing 12 (e.g., a plurality of ribs 58). The plurality of ribs 58 can be formed along the inner wall 29 of the strainer housing 12. The plurality of ribs 58 can be integrally formed or permanently fastened with the inner wall 29. By way of a non-limiting example, the plurality of ribs 58 can be molded into the inner wall 29. Alternatively, the plurality of ribs 58 can be mechanically fastened with the inner wall 29 to allow for the removal of the ribs if debris removal is required or if it is desired that the pump 10 be converted from a dedicated water feature pump to a traditional filtration pump. The plurality of ribs 58 can extend outwardly from the inner wall 29. The plurality of ribs 58 can each be shaped in a triangular fashion or any other shape suitable for preventing installation of a strainer basket. In some embodiments, the ribs are removably received by the strainer housing (e.g., in receiving grooves/channels formed therein). The plurality of ribs 58 can have a top side 60 and a distal end 62. The shape of the plurality of ribs 58, including the length of the top side 60 and the distal end 62, can be of any shape, length and thickness to prevent installation of a strainer basket. The shape of the plurality of ribs 58, including the length of the top side 60 and the distal end 62, can also be of any shape, length and thickness to allow for enough water to fill the reservoir 30 to allow the pump 10 to self-prime. The plurality of ribs 58 can be circumferentially displaced with respect to the reservoir 32 to prevent the installation of a strainer basket. The amount of the plurality of ribs 58 can be any number sufficient to prevent the installation of a strainer basket while allowing enough water to fill the reservoir 32 to allow the pump 10 to self-prime.

An alternate embodiment of the water feature pump 10 is shown in FIG. 8. In this embodiment, the strainer housing 12 is installed remotely from the pump housing 14. The strainer housing 12 can be installed at a higher vertical level than the pump housing 14 or at the same level as the pump housing 14. Positioning the strainer housing 12 above the pump housing 14 allows the strainer housing to maintain a constant flooded system to allow the pump 10 to self-prime. Any of the prevention means discussed in the present application for preventing a strainer basket from being installed in the strainer housing 12 can also be used in this embodiment. Any of the prevention means can be permanently fastened to the strainer housing 12 or can optionally be removable. A pipe 63 can be used to connect the strainer housing 12 to the pump housing 14 to allow water to flow from the strainer housing 12 to the pump housing 14. The pipe 63 can be any

suitable size. The pipe 63 can be over-sized, for example. The pipe can be, for example, 8 inches and include a body for a 2-2.5 inch system.

Referring to FIG. 9, an embodiment is shown schematically. In this embodiment, a prevention means for preventing a top cover 64 is placed over the strainer housing 12 to prevent the installation of a strainer basket in the strainer housing 12. The top cover 64 is placed over the entirety of the top end 24 of the strainer housing such that the reservoir 32 is covered. The top cover 64 can be secured to the strainer housing 12 with a flange connection 66. Any other suitable means of connecting the top cover 64 with the strainer housing 12 can be used. In this embodiment, the reservoir is “flipped” to prevent top entry in the strainer housing 12. As with other embodiments, the top cover 64 can be permanently secured to the strainer housing 12 or it can be removably secured to allow for debris removal or the conversion from a dedicated water feature pump to a traditional filtration pump.

An alternate embodiment of the water feature pump 10 is shown in FIG. 10. In this embodiment, a prevention means for preventing the installation of a strainer basket in the strainer housing 12 can be installed with the strainer housing 12. The prevention means can be a perforated means for preventing the installation of a strainer basket in the strainer housing 12 (e.g., a screen 68). The screen 68 can be integrally formed with the strainer housing 12 to prevent installation of a strainer basket in the reservoir 32. The screen 68 can alternatively be permanently mechanically fastened to the strainer housing 12. The screen 68 can also be removably fastened to the strainer housing 12 to allow for debris removal or to allow the pump 10 to be converted from a dedicated water feature pump to a traditional filtration pump. The screen 68 can include a plurality of apertures 70. The screen 68 can be installed at the top end 24, above the reservoir 32. This would allow for enough water to fill the reservoir 32 to allow the pump 10 to self-prime while also preventing the installation of a strainer basket. The screen 68 can be a grate, mesh or similar type of perforated/grated feature.

Having thus described the invention in detail, it is to be understood that the foregoing description is not intended to limit the spirit or scope thereof. It will be understood that the embodiments of the present invention described herein are merely exemplary and that a person skilled in the art may make any variations and modification without departing from the spirit and scope of the invention. All such variations and modifications, including those discussed above, are intended to be included within the scope of the invention.

What is claimed is:

1. A dedicated water feature pump comprising:
a base;
a strainer housing connected to the base and extending upwardly with respect to the base, the strainer housing defining a reservoir for receiving water through an inlet and an inner wall;
a pump housing connected to the strainer housing and extending rearwardly with respect to the strainer housing;
a prevention means installed in the reservoir for preventing installation of a strainer basket in the strainer housing;
wherein the strainer housing allows the pump to self-prime by preventing a strainer basket from being installed in the strainer housing.
2. The dedicated water feature pump of claim 1, wherein the prevention means is a post.

3. The dedicated water feature pump of claim 2, comprising a cap installed on the post to further prevent installation of a strainer basket in the strainer housing.

4. The dedicated water feature pump of claim 1, comprising a hole between the strainer housing and the pump housing to allow water to flow from the strainer housing to the pump housing.

5. The dedicated water feature pump of claim 4 in combination with a water feature, said water feature being one of a spa jet, waterfall/sheer fall, rain curtain, fountain, deck jet, laminar jet, bubbler, scupper, spillover, vanishing/negative edge, or misting/fog system.

6. The combination of claim 5, wherein said pump housing has an outlet for communicating water to said water feature via an outflow conduit.

7. The dedicated water feature pump of claim 2, wherein the post is removable to allow for the removal of debris from the strainer housing and to allow the pump to be used as a filtration pump.

8. A dedicated water feature pump comprising:

a base;
a strainer housing connected to the base and extending upwardly with respect to the base, the strainer housing defining a reservoir for receiving water through an inlet and an inner wall;

a pump housing connected to the strainer housing and extending rearwardly with respect to the strainer housing;

a cover installed over the strainer housing for preventing a strainer basket from being installed in the reservoir; wherein the strainer housing allows the pump to self-prime absent the strainer basket.

9. The dedicated water feature pump of claim 8, comprising an extended wall extending downward from the cover, the extended wall having an aperture corresponding to the inlet of the strainer housing to allow water to enter the reservoir.

10. The dedicated water feature pump of claim 8, comprising a hole between the strainer housing and the pump housing to allow water to flow from the strainer housing to the pump housing.

11. The dedicated water feature pump of claim 8 in combination with a water feature, said water feature being one of a spa jet, waterfall/sheer fall, rain curtain, fountain, deck jet, laminar jet, bubbler, scupper, spillover, vanishing/negative edge, or misting/fog system.

12. The combination of claim 11, wherein said pump housing has an outlet for communicating water to said water feature via an outflow conduit.

13. The dedicated water feature pump of claim 8, wherein the cover is removable to allow for the removal of debris from the strainer housing and to allow the pump to be used as a filtration pump.

14. A dedicated water feature pump comprising:

a base;
a strainer housing connected to the base and extending upwardly with respect to the base, the strainer housing defining a reservoir for receiving water through an inlet and an inner wall;

a pump housing connected to the strainer housing and extending rearwardly with respect to the strainer housing;

a plurality of ribs installed in the reservoir for preventing a strainer basket from being installed in the reservoir; wherein the strainer housing allows the pump to self-prime absent the strainer basket.

15. The dedicated water feature pump of claim 14, wherein at least one of the plurality of ribs is triangularly shaped.

16. The dedicated water feature pump of claim 14, comprising a hole between the strainer housing and the pump housing to allow water to flow from the strainer housing to the pump housing.

17. The dedicated water feature pump of claim 14 in combination with a water feature, said water feature being one of a spa jet, waterfall/sheer fall, rain curtain, fountain, deck jet, laminar jet, bubbler, scupper, spillover, vanishing/negative edge, or misting/fog system.

18. The combination of claim 17, wherein said pump housing has an outlet for communicating water to said water feature via an outflow conduit.

19. The dedicated water feature pump of claim 14, wherein at least one of the plurality of ribs is removable to allow for the removal of debris from the strainer housing and to allow the pump to be used as a filtration pump.

20. A dedicated water feature pump comprising:
a strainer housing defining a reservoir for receiving water through an inlet and an inner wall, the strainer housing including a means for preventing a strainer basket from being installed in the strainer housing;
a pump housing connected to the strainer housing through a pipe, the pump housing being installed at a lower vertical level with respect to the strainer housing; wherein the position of the strainer housing with respect to the pump housing allows the strainer housing to be flooded with water to allow the pump to self-prime.

21. The dedicated water feature pump of claim 20, wherein the prevention means includes at least one of a post, a screen, and a top cover.

22. The dedicated water feature pump of claim 20 in combination with a water feature, said water feature being one of a spa jet, waterfall/sheer fall, rain curtain, fountain, deck jet, laminar jet, bubbler, scupper, spillover, vanishing/negative edge, or misting/fog system.

23. The combination of claim 22, wherein said pump housing has an outlet for communicating water to said water feature via an outflow conduit.

24. The dedicated water feature pump of claim 20, wherein the prevention means is removable to allow for the removal of debris from the strainer housing and to allow the pump to be used as a filtration pump.

25. A dedicated water feature pump comprising:
a base;
a priming reservoir housing connected to the base and extending upwardly with respect to the base, the priming reservoir housing defining a reservoir for receiving water through an inlet and an inner wall;
a pump housing connected to the priming reservoir housing and extending rearwardly with respect to the priming reservoir housing;
a perforated means for preventing the installation of a strainer basket in the priming reservoir housing installed above the reservoir; wherein the priming reservoir housing allows the pump to self-prime absent the strainer basket.

26. The dedicated water feature pump of claim 25, wherein the perforated means includes at least one of a screen, a grate, or a mesh.

27. The dedicated water feature pump of claim 25, comprising a hole between the priming reservoir and the pump housing to allow water to flow from the priming reservoir housing to the pump housing.

28. The dedicated water feature pump of claim 25 in combination with a water feature, said water feature being one of a spa jet, waterfall/sheer fall, rain curtain, fountain, deck jet, laminar jet, bubbler, scupper, spillover, vanishing/negative edge, or misting/fog system. 5

29. The combination of claim 27, wherein said pump housing has an outlet for communicating water to said water feature via an outflow conduit.

30. The dedicated water feature pump of claim 25, wherein the perforated means is removable to allow for the 10 removal of debris from the priming reservoir housing and to allow the pump to be used as a filtration pump.
